UNITED STATES PATENT OFFICE.

EDWARD L. SCHIEFER, OF ST. LOUIS, MISSOURI.

GARBAGE CAN OR RECEPTACLE.

SPECIFICATION forming part of Letters Patent No. 719,515, dated February 3, 1903.

Application filed December 2, 1902. Serial No. 133,558. (No model.)

To all whom it may concern:

Be it known that I, EDWARD L. SCHIEFER, a citizen of the United States, residing at St. Louis, in the State of Missouri, have invented new and useful Improvements in Garbage Cans or Receptacles, of which the following is a specification.

This invention relates to cans or receptacles adapted for receiving and holding garbage, ashes, and general refuse, and particularly to simple and effective devices in this class of cans for making an air-tight joint between the hinged cover and the bearing rim at top of the can.

15 The object of my invention is to provide a can or receptacle which is strong and simple in construction and which shall be convenient, durable, and effective in operation.

A special object of my invention is to provide a spring-flange made as an integral part of the cover and adapted for receiving and clamping in place a packing of rubber, leather, or other flexible material for making a tight joint between the cover and the bearing rim 25 or band at the top of the can or other form of receptacle, and thereby preventing the escape of noxious gases and odors from the contained garbage.

My can or receptacle is of a suitable character to be placed in a vault or other convenient place for the collection of garbage.

The devices and features of construction constituting my invention herein will be particularly described, and then defined in the 35 claims.

I will now describe the details of construction and operation of my improved can by reference to the accompanying drawings, in which—

40 Figure 1 represents a front elevation of the can with the cover closed. Fig. 2 represents a vertical section thereof. Fig. 3 represents a sectional detail, on enlarged scale, of the band or rim at the top of the can. Fig. 4 represents a sectional detail, on enlarged scale, of the spring-flange and packing at the rear edge of the cover. Fig. 5 represents a 45 sectional detail, on enlarged scale, of the spring-flange and packing as constructed at the side and front edges of the cover.

The body of the can or receptacle 1 is made of galvanized iron or other suitable sheet

metal and preferably square or rectangular in cross-section and provided with suitable reinforcing and strengthening parts to make 55 it strong and durable to resist the rough usage to which such a can is subjected. The bottom 2 is secured to the side walls in any desired manner. The can is provided with a hinged cover or lid 3, connected by hinges 3^a 60 at its rear edge to the can-body or the band 4. The reinforcing and strengthening band 4 is made by bending the upper edges of the metal in the body downward and over a strip or band 5, of iron or other metal, and bending the edge 4^a up between the band 5 and the body 1, as shown in Fig. 3. The band is preferably made of heavy malleable iron in a continuous band or bent piece, so as to suitably strengthen the top of the can and form 70 a bearing-rim 1^a at the top, with a rounded smooth finish, as shown in Fig. 3. A reinforcing and strengthening band 6, about three inches wide or high, is secured to the lower end of the body, so as to project below the 75 bottom 2 and protect the same, as shown in Fig. 2. When a flange of the bottom 2 is turned up in the body, as shown, such flange and the band 6 may be secured to the body by rivets passing through the three parts, so 80 as to securely and tightly hold them together. The band 6 is preferably provided with a series of ventilating-holes 7. The four corners of the body 1 are protected by upright strips of angle-iron 8, each of which fits over two adjacent sides at the corner and serve to strengthen 85 and protect the body from rough usage, especially when the can is tilted and rested against another receptacle when being emptied. Other vertical strips or ribs may be secured to the body between the corner-irons 8, if desired, for further strengthening the can. Lateral handles 9 are pivoted to the lugs 10, secured to the opposite sides of the can for carrying it, and a similar handle (not 90 here shown) may be secured lower down to the back of the can for convenience in tilting the can when it is to be emptied. To the front edge of the cover is secured a spring catch or clasp 3^b, adapted to engage with the band 4, 95 and is provided with a handle-ring 3^c, as shown in Fig. 1.

The edges of the metal forming the cover 3 are bent downward and inward to form the

spring-flanges 14, containing the flexible packing material 16. The rear edge of the cover is bent as shown in Fig. 4 for convenience in applying the hinges 3^a. A sufficiently wide strip of metal is bent downward to form the vertical member 12 and is then bent inward and back upon itself, forming member 13, and again inward and inclined downward from the top 3 to form the groove 11, (shown in Fig. 4,) and the inner edge is turned over and outward, as an overlapping lip 15, to form the groove 11^a. The flexible packing of rubber or leather or other suitable material 16 is inserted by its edges in the grooves 11 and 11^a and clamped in place by the member 13 and the lip 15. The side and front edges of the cover are bent as shown in Fig. 5, the member 13^a being bent back on member 12 to the top 3 to form a downwardly-projecting side flange for overlapping the top band 4 of the can. The downwardly-inclined flange portion 14, holding the rubber or other packing 16, acts as a spring to bear by yielding pressure upon the rim 1^a of the band 4 and make therewith an air-tight joint to prevent the escape of any objectionable odors from the contents of the can. I regard this spring-flange as an important and valuable feature of my invention, and it may be somewhat varied in details without departing from my invention.

Having described my invention, what I claim, and desire to secure by Letters Patent, is—

1. The combination with the can-body, having bearing-rim at the top, of a cover having inwardly-turned spring-flanges containing a

packing of flexible material and adapted to bear by spring-pressure on the rim to make a tight joint substantially as and for the purpose described. 40

2. The combination with the body of the can or other receptacle, made with a top reinforcing and strengthening band forming a bearing-rim, of a cover having downwardly and inwardly bent spring-flanges containing a 45 packing of flexible material clamped thereto by folds of the metal for bearing by spring-pressure on said rim, substantially as and for the purpose described.

3. The combination with the body of the can 50 or receptacle, having a strengthening and bearing rim at the top, of the hinged cover having inwardly-bent yielding spring-flanges for bearing, by spring-pressure, on the rim to make a tight joint, and a spring clasp or 55 catch for engaging with said band or rim to hold the spring-flanges on their seat substantially as and for the purpose described.

4. In combination with the can-body, the cover having spring-flanges made integral 60 therewith and comprising a vertical member folded upon itself and a horizontal or inwardly-inclined member forming a spring and bent to engage or clamp a packing and a flexible packing on said spring member substantially as and for the purpose described. 65

In testimony whereof I affix my signature in presence of two witnesses.

EDWARD L. SCHIEFER.
